UNITED STATES PATENT OFFICE

2,424,739

MOTION-PICTURE PROJECTOR

Don Canady, Cleveland, Ohio

Application March 7, 1944, Serial No. 525,451

3 Claims. (Cl. 242—75)

1

This invention relates primarily to a take-up reel support for motion picture projectors, although it will be apparent that the device may be used with various other mechanisms wherein it is desired to increase the tension on a winding reel as the size increases. It is desirable in take-up reel supports to provide means for increasing the tension on the driving means as the film on the reel increases in weight.

The object of my invention is to provide a friction clutch driving mechanism for a take-up reel whereby the weight of the reel will lead the clutch.

A further object of my invention is to provide an arm supported pivoted on the frame carrying a driven shaft and a film reel driving shaft, whereby the weight of the reel winding up the film will create a pressure on a friction clutch between the driven shaft and the drive shaft.

My invention will be further readily understood from the following description and claims, and from the drawings, in which latter:

Fig. 1 is a plan view of my improved mechanism; and,

Fig. 2 is a side view of the same.

My improved device comprises an arm 11 pivoted to the frame of the projector as at 12. When the projector is not in use, the arm may be removed from or folded onto the machine 13. A shaft 14 extending from the projector is provided with one part of a friction clutch 15. The arm 11 carries a shaft 16 having the other portion 17 of the friction clutch attached thereto. The other end of the shaft 16 is provided with a bevel gear 18 meshing with a bevel gear 19 on a cross-shaft 20 journalled in the end of the arm 11. This cross-shaft is provided with a suitable film reel engaging portion 21.

The take-up reel on a movie projector, while being driven, must keep a tension on the film and have some form of slippage in the drive to compensate for the increased diameter of the film on the reel. With my improved structure, the clutch permits the film shaft to rotate at a speed sufficient to roll up the film on the reel and as the reel becomes loaded the added weight increase the tension on the friction clutch to continue to drive the reel with the proper friction being applied.

Having thus fully described my invention, what I claim as new and desire to secure by Letters Patent, is:

2

1. A take-up device comprising a frame, a drive shaft carried by said frame, an arm pivoted to said frame and having a portion extending substantially parallel to said drive shaft, a driven shaft carried by said arm movable into axial alignment with said drive shaft, a friction clutch interposed between the ends of said shafts, and a transverse reel shaft mounted in the end of said arm and driven by said driven shaft.
- 10 2. A take-up device comprising a frame, a drive shaft carried by said frame, an arm pivoted to said frame and having a portion extending substantially parallel to said drive shaft, a driven shaft carried by said arm movable into axial alignment with said drive shaft, a reel shaft mounted in the end of said arm and having driving connection with said driven shaft, and a friction clutch interposed between the ends of said drive shaft and said driven shaft whereby increased weight on said reel shaft will increase the friction in said friction clutch.
- 15 3. A take-up device for a movie projector comprising a frame, a drive shaft journalled on said frame, a friction member secured to the end of said shaft, an arm pivoted on said frame movable to extend in axial alignment with said shaft, a driven shaft carried by said arm and movable into axial alignment with said drive shaft, a friction member secured to one end of said driven shaft mating with said first named friction member, a film reel shaft geared to the extending end of said driven shaft whereby increased weight on said film reel shaft will increase the friction between said friction members.
